(57) **ABSTRACT**

An active noise control device includes an updated value table operating unit that writes initial values of an initial value table into an updated value table as updated values and writes updated coefficients of a secondary path filter C^* updated in a secondary path filter coefficient updating unit during active noise control, into the updated value table as updated values. The secondary path filter coefficient updating unit reads the updated value corresponding to a frequency from the updated value table before updating the coefficients of the secondary path filter C^* , and updates the coefficients of the secondary path filter C^* , using the read updated values as the previous values.

ACTIVE NOISE CONTROL DEVICE

CROSS-REFERENCE TO RELATED APPLICATIONS

This application is based upon and claims the benefit of priority from Japanese Patent Applications No. 2020-062570 filed on Mar. 31, 2020 and No. 2021-018455 filed on Feb. 8, 2021, the contents all of which are incorporated herein by reference.

BACKGROUND OF THE INVENTION

Field of the Invention

The present invention relates to an active noise control device that performs active noise control by controlling a speaker based on an error signal that changes in accordance with a combined sound of a noise transmitted from a vibration source and an anti-noise sound output from the speaker in order to cancel the noise.

Description of the Related Art

Japanese Laid-Open Patent Publication No. 2008-239098 discloses a system in which a standard signal is generated based on the rotation frequency of the propeller shaft, and the generated standard signal is then signal-processed through an adaptive filter to generate a control signal for outputting an anti-noise sound from a speaker so as to cancel out noise transmitted from the propeller shaft into the vehicle. In this system, the adaptive filter is updated based on an error signal output by a microphone installed in the vehicle and a reference signal generated by correcting the standard signal with a correction value.

SUMMARY OF THE INVENTION

In Japanese Laid-Open Patent Publication No. 2008-239098, since the transfer characteristic of the anti-noise sound between the speaker and the microphone is measured in advance and the measured characteristic is used as correction values, there is a concern that the noise cannot be reduced if the transfer characteristic changes.

The present invention has been devised to solve the above problem, it is therefore an object of the present invention to provide an active noise control device capable of reducing noise even if the transfer characteristic changes.

An aspect of the present invention resides in an active noise control device that performs active noise control for controlling a speaker based on an error signal that changes in accordance with the combined sound of a noise transmitted from a vibration source and an anti-noise sound for cancelling the noise, output from the speaker, the active noise control device including: a standard signal generation unit configured to generate a standard signal in accordance with a control target frequency; a control signal generation unit configured to generate a control signal for controlling the speaker by signal-processing the standard signal through a control filter that is an adaptive notch filter; an estimated noise signal generation unit configured to generate an estimated noise signal by signal-processing the standard signal through a primary path filter that is an adaptive notch filter; a first estimated anti-noise signal generation unit configured to generate a first estimated anti-noise signal by signal-processing the control signal through a secondary path filter that is an adaptive notch filter; a reference signal generation

unit configured to generate a reference signal by signal processing the standard signal through the secondary path filter; a second estimated anti-noise signal generation unit configured to generate a second estimated anti-noise signal by signal-processing the reference signal through the control filter; a first virtual error signal generation unit configured to generate a first virtual error signal from the error signal, the first estimated anti-noise signal and the estimated noise signal; a second virtual error signal generation unit configured to generate a second virtual error signal from the second estimated anti-noise signal and the estimated noise signal; a secondary path filter coefficient updating unit configured to successively and adaptively update the coefficients of the secondary path filter so as to minimize the magnitude of the first virtual error signal, based on the control signal and the first virtual error signal; a control filter coefficient updating unit configured to successively and adaptively update the coefficients of the control filter so as to minimize the magnitude of the second virtual error signal, based on the reference signal and the second virtual error signal; an initial value table configured to store initial values of the coefficients of the secondary path filter in association with a frequency, in a table format; an updated value table configured to store updated values of the coefficients of the secondary path filter in association with the frequency, in a table format; an updated value table operating unit configured to write the initial values of the initial value table into the updated value table as the updated values at the start of the active noise control and write the coefficients of the secondary path filter updated by the secondary path filter coefficient updating unit during the active noise control, into the updated value table as the updated values, wherein the secondary path filter coefficient updating unit is configured to read the updated values corresponding to the frequency from the updated value table before updating the coefficients of the secondary path filter, and update the coefficients of the secondary path filter, using the read updated values as the previous values.

The active noise control device of the present invention can reduce noise even if the transfer characteristic changes.

The above and other objects, features, and advantages of the present invention will become more apparent from the following description when taken in conjunction with the accompanying drawings, in which preferred embodiments of the present invention are shown by way of illustrative example.

BRIEF DESCRIPTION OF THE DRAWINGS

FIG. 1 is a diagram illustrating an outline of active noise control;

FIG. 2 is a block diagram of an active noise control device;

FIG. 3 is a block diagram of the active noise control device;

FIG. 4 is a diagram for explaining the updating of filter coefficients;

FIG. 5 is a flowchart showing the flow of a filter coefficient update process;

FIG. 6A is a diagram showing gain characteristics of a secondary path transfer characteristic, FIG. 6B is a diagram showing phase characteristics of the secondary path transfer characteristic;

FIG. 7 is a graph showing the sound pressure levels of noise in the vehicle passenger compartment;

FIG. 8 is a graph showing the sound pressure levels of noise in the vehicle passenger compartment;

FIG. 9 is a graph showing the sound pressure levels of noise in the vehicle passenger compartment;

FIG. 10 is a graph showing phase characteristics of updated values;

FIG. 11 is a graph showing the sound pressure levels of noise in the vehicle passenger compartment;

FIG. 12 is a graph showing phase characteristics of updated values;

FIG. 13 is a graph showing phase characteristics of updated values;

FIG. 14 is a graph showing the sound pressure levels of noise in the vehicle passenger compartment;

FIG. 15 is a graph showing the sound pressure levels of noise in the vehicle passenger compartment;

FIG. 16 is a block diagram of a signal processing unit;

FIG. 17 is a block diagram of a signal processing unit;

FIG. 18 is a block diagram of a signal processing unit;

FIG. 19 is a block diagram of a signal processing unit;

FIG. 20 is a block diagram of a signal processing unit;

FIG. 21 is a graph showing the amplitudes of control filters; and

FIG. 22 is a graph showing the sound pressure levels of noise in the vehicle passenger compartment.

DESCRIPTION OF THE PREFERRED EMBODIMENTS

First Embodiment

FIG. 1 is a diagram illustrating an outline of active noise control achieved by an active noise control device 10.

The active noise control device 10 outputs an anti-noise sound from a speaker 16 installed in a vehicle passenger compartment 14 of a vehicle 12, so as to reduce the engine's booming noise (hereinafter referred to as noise) transmitted to the occupant in the vehicle passenger compartment 14 resulting from the vibration of an engine 18. The active noise control device 10 generates a control signal u_0 for causing the speaker 16 to output an anti-noise sound based on an error signal e output from a microphone 22 arranged on a headrest 20a of a seat 20 in the vehicle passenger compartment 14 and the engine speed Ne detected by an engine speed sensor 24. The error signal e is a signal that is output according to a canceling error noise from the microphone 22 detecting the canceling error noise which is a combination of the anti-noise sound and the noise.

Conventional Active Noise Control Device

Conventionally, there has been proposed an active noise control device which uses adaptive notch filters (for example, SAN (Single-frequency Adaptive Notch) filters) that need a limited amount of arithmetic processing.

In the conventional active noise control device, first, a standard signal x having a frequency (control target frequency) of noise to be canceled is generated. The generated standard signal x is signal-processed through a control filter W as an adaptive notch filter to produce a control signal u_0 . This control signal u_0 is used to control the speaker 16 and cause the speaker 16 to output an anti-noise sound for canceling out the noise.

The control filter W is updated by an adaptive algorithm (for example, LMS (Least Mean Square) algorithm) so as to minimize the error signal e output from the microphone 22.

However, since a transfer characteristic C exists in the transmission path between the speaker 16 and the microphone 22, it is necessary to consider this transfer character-

istic C when updating the control filter W . The transfer characteristic C also includes electronic circuit characteristics and the like. Therefore, the transfer characteristic C is identified in advance as a filter C' , and the standard signal x corrected by the filter C' is used to update the control filter W . This control system is called a Filtered-X type.

Since the filter C' is a fixed filter identified in advance, a difference may occur between the filter C' and the transfer characteristic C when the transfer characteristic C changes. In this case, the control filter W may diverge due to updating, and there is a risk that noise amplification and/or abnormal noise occur.

Therefore, the present inventors hereof have proposed a method which allows the filter C' to follow the change in the transfer characteristic C during active noise control without the need to identify the transfer characteristic C in advance. The present invention is a further improvement to the method that was already proposed by the present inventors hereof. Now, the outline of an active noise control device 100 using the method already proposed by the present inventors will be described below.

FIG. 2 is a block diagram of the active noise control device 100 using the method that was already proposed by the present inventors. The transmission path from the engine 18 to the microphone 22 may be referred to hereinbelow as a primary path. Further, the transmission path from the speaker 16 to the microphone 22 may be referred to as a secondary path below.

The active noise control device 100 includes a standard signal generation unit 26, a control signal generation unit 28, a first estimated anti-noise signal generation unit 30, an estimated noise signal generation unit 32, a reference signal generation unit 34, a second estimated anti-noise signal generation unit 36, a primary path filter coefficient updating unit 38, a secondary path filter coefficient updating unit 40 and a control filter coefficient updating unit 42.

The standard signal generation unit 26 generates standard signals xc and xs based on the engine speed Ne . The standard signal generation unit 26 includes a frequency detection circuit 26a, a cosine signal generator 26b and a sine signal generator 26c.

The frequency detection circuit 26a detects a control target frequency f . The control target frequency f is the vibration frequency of the engine 18 detected based on the engine speed Ne . The cosine signal generator 26b generates a standard signal xc ($=\cos(2\pi ft)$) which is a cosine signal of the control target frequency f . The sine signal generator 26c generates a standard signal xs ($=\sin(2\pi ft)$) which is a sine signal of the control target frequency f . Here, t is time.

The control signal generation unit 28 generates control signals u_0 and u_1 based on the standard signals xc and xs . The control signal generation unit 28 includes a first control filter 28a, a second control filter 28b, a third control filter 28c, a fourth control filter 28d, an adder 28e and an adder 28f.

In the control signal generation unit 28, a SAN filter is used for a control filter W . The control filter W includes a filter W_0 for the standard signal xc and a filter W_1 for the standard signal xs . The control filter W is optimized by updating a coefficient W_0 of the filter W_0 , and a coefficient W_1 of the filter W_1 , in the control filter coefficient updating unit 42 described later.

The first control filter 28a has a filter coefficient W_0 . The second control filter 28b has a filter coefficient W_1 . The third control filter 28c has a filter coefficient $-W_0$. The fourth control filter 28d has a filter coefficient W_1 .

The standard signal xc corrected by the first control filter **28a** and the standard signal xs corrected by the second control filter **28b** are added at the adder **28e** to generate the control signal $u0$. The standard signal xs corrected by the third control filter **28c** and the standard signal xc corrected by the fourth control filter **28d** are added at the adder **28f** to generate the control signal $u1$.

The control signal $u0$ is converted into an analog signal by a digital-to-analog converter **17** and output to the speaker **16**. The speaker **16** is controlled based on the control signal $u0$ and outputs anti-noise sound from the speaker **16**.

The first estimated anti-noise signal generation unit **30** generates a first estimated anti-noise signal $y1^*$ based on the control signals $u0$ and $u1$. The first estimated anti-noise signal generation unit **30** includes a first secondary path filter **30a**, a second secondary path filter **30b** and an adder **30c**.

In the first estimated anti-noise signal generation unit **30**, a SAN filter is used for the secondary path filter C^* . In the secondary path filter coefficient updating unit **40** detailed later, the complex-valued coefficient ($C0^*+iC1^*$ where “i” is the imaginary unit) of the secondary path filter C^* is updated, whereby the sound transfer characteristic C is identified as the secondary path filter C^* .

The first secondary path filter **30a** has a filter coefficient, $C0^*$, which is the real part of the coefficient of a secondary path filter C^* . The second secondary path filter **30b** has a filter coefficient, $C1^*$, which is the imaginary part of the coefficient of the secondary path filter C^* . The control signal $u0$ corrected by the first secondary path filter **30a** and the control signal $u1$ corrected by the second secondary path filter **30b** are added at the adder **30c** to generate the first estimated anti-noise signal $y1^*$. The first estimated anti-noise signal $y1^*$ is the estimated signal of the signal corresponding to an anti-noise sound y input to the microphone **22**.

The estimated noise signal generation unit **32** generates an estimated noise signal d^* based on the standard signals xc and xs . The estimated noise signal generation unit **32** includes a first primary path filter **32a**, a second primary path filter **32b** and an adder **32c**.

In the estimated noise signal generation unit **32**, a SAN filter is used for a primary path filter H^* . In the primary path filter coefficient updating unit **38**, which will be described later, the complex-valued coefficient ($H0^*+iH1^*$ where “i” is the imaginary unit) of the primary path filter H^* is updated, whereby the transfer characteristic H , of the primary path (hereinafter, referred as the primary path transfer characteristic H) is identified as the primary path filter H^* .

The first primary path filter **32a** has a filter coefficient, $H0^*$, which is the real part of the coefficient of the primary path filter H^* . The second primary path filter **32b** has a filter coefficient $-H1^*$, which is a value obtained by inverting the polarity of the imaginary part of the coefficient of the extraction filter H^* . The standard signal xc corrected by the first primary path filter **32a** and the standard signal xs corrected by the second primary path filter **32b** are added at the adder **32c** to generate an estimated noise signal d^* . The estimated noise signal d^* is an estimated signal of a signal corresponding to the noise d input to the microphone **22**.

The reference signal generation unit **34** generates reference signals $r0$ and $r1$ based on the standard signals xc and xs . The reference signal generation unit **34** includes a third secondary path filter **34a**, a fourth secondary path filter **34b**, a fifth secondary path filter **34c**, a sixth secondary path filter **34d**, an adder **34e** and an adder **34f**.

In the reference signal generation unit **34**, a SAN filter is used for a secondary path filter C^* . In the secondary path

filter coefficient updating unit **40** described later, the complex-valued coefficient ($C0^*+iC1^*$ where “i” is the imaginary unit) of the secondary path filter C^* is updated, whereby the transfer characteristic C of the secondary path (hereinafter referred to as the secondary path transfer characteristic C) is identified as the secondary pathway filter C^* .

The third secondary path filter **34a** has a filter coefficient $C0^*$, which is the real part of the coefficient of the secondary path filter C^* . The fourth secondary path filter **34b** has a filter coefficient $-C1^*$, which is a value obtained by inverting the polarity of the imaginary part of the coefficient of the secondary path filter C^* . The fifth secondary path filter **34c** has a filter coefficient $C0^*$, which is the real part of the coefficient of the secondary path filter C^* . The sixth secondary path filter **34d** has a filter coefficient $C1^*$, which is the imaginary part of the coefficient of the secondary path filter C^* .

The standard signal xc corrected by the third secondary path filter **34a** and the standard signal xs corrected by the fourth secondary path filter **34b** are added at the adder **34e** to generate the reference signal $r0$. The standard signal xs corrected by the fifth secondary path filter **34c** and the standard signal xc corrected by the sixth secondary path filter **34d** are added at the adder **34f** to generate the reference signal $r1$.

The second estimated anti-noise signal generation unit **36** generates a second estimated anti-noise signal $y2^*$ based on the reference signals $r0$ and $r1$. The second estimated anti-noise signal generation unit **36** includes a fifth control filter **36a**, a sixth control filter **36b** and an adder **36c**.

In the second estimated anti-noise signal generation unit **36**, a SAN filter is used for a control filter W . The fifth control filter **36a** has a filter coefficient $W0$. The sixth control filter **36b** has a filter coefficient $W1$.

The reference signal $r0$ corrected by the fifth control filter **36a** and the reference signal $r1$ corrected by the sixth control filter **36b** are added at the adder **36c** to generate the second estimated anti-noise signal $y2^*$. The second estimated anti-noise signal $y2^*$ is an estimated signal of a signal corresponding to the anti-noise sound y input to the microphone **22**.

An analog-digital converter **44** converts the error signal e output from the microphone **22** from an analog signal to a digital signal.

The error signal e is input to an adder **46**. The estimated noise signal d^* generated by the estimated noise signal generation unit **32** passes through an inverter **48** where its polarity is inverted and then the inverted signal is input to the adder **46**. The first estimated anti-noise signal $y1^*$ generated by the first estimated anti-noise signal generation unit **30** passes through an inverter **50** where its polarity is inverted and then the inverted signal is input to the adder **46**. In the adder **46**, a first virtual error signal $e1$ is generated. The adder **46** corresponds to the first virtual error signal generation unit of the present invention.

The estimated noise signal d^* generated by the estimated noise signal generation unit **32** is input to an adder **52**. The second estimated anti-noise signal $y2^*$ generated by the second estimated anti-noise signal generation unit **36** is input to the adder **52**. In the adder **52**, a second virtual error signal $e2$ is generated. The adder **52** corresponds to the second virtual error signal generation unit of the present invention.

The primary path filter coefficient updating unit **38** updates the filter coefficients $H0^*$ and $H1^*$, based on the standard signals xc and xs and the first virtual error signal $e1$. The primary path filter coefficient updating unit **38** updates

the filter coefficients $H0^\wedge$ and $H1^\wedge$, based on an LMS algorithm. The primary path filter coefficient updating unit 38 includes a first primary path filter coefficient updating unit 38a and a second primary path filter coefficient updating unit 38b.

The first primary path filter coefficient updating unit 38a and the second primary path filter coefficient updating unit 38b update the filter coefficients $H0^\wedge$ and $H1^\wedge$ based on the following equations. In the equations, n is a time step (n=0, 1, 2, . . .), and $\mu0$ and $\mu1$ are step size parameters.

$$H0^\wedge_{n+1} = H0^\wedge_n - \mu0 \times e1_n \times x_{C_n}$$

$$H1^\wedge_{n+1} = H1^\wedge_n - \mu1 \times e1_n \times x_{S_n}$$

In the primary path filter coefficient updating unit 38, the filter coefficients $H0^\wedge$ and $H1^\wedge$ are repeatedly updated, so that the primary path transfer characteristic H is identified as the primary path filter $H^\wedge$. In the active noise control device 100 using SAN filters, the updating formulae of the coefficients of the primary path filter $H^\wedge$ are defined by four arithmetic operations and include no convolution operation. Therefore, the calculation load due to the updating process of the filter coefficients $H0^\wedge$ and $H1^\wedge$ can be reduced.

The secondary path filter coefficient updating unit 40 updates the filter coefficients $C0^\wedge$ and $C1^\wedge$ based on the control signals $u0$ and $u1$ and the first virtual error signal $e1$. The secondary path filter coefficient updating unit 40 updates the filter coefficients $C0^\wedge$ and $C1^\wedge$ based on the LMS algorithm. The secondary path filter coefficient updating unit 40 includes a first secondary path filter coefficient updater 40a and a second secondary path filter coefficient updater 40b.

The first secondary path filter coefficient updater 40a and the second secondary path filter coefficient updater 40b update the filter coefficients $C0^\wedge$ and $C1^\wedge$ based on the following equations, where $\mu2$ and $\mu3$ are step size parameters.

$$C0^\wedge_{n+1} = C0^\wedge_n - \mu2 \times e1_n \times u0_n$$

$$C1^\wedge_{n+1} = C1^\wedge_n - \mu3 \times e1_n \times u1_n$$

In the secondary path filter coefficient updating unit 40, the filter coefficients $C0^\wedge$ and $C1^\wedge$ are repeatedly updated, so that the secondary path transfer characteristic C is identified as the secondary path filter $C^\wedge$. In the active noise control device 100 using SAN filters, the updating formulae of the filter coefficients $C0^\wedge$ and $C1^\wedge$ are defined by four arithmetic operations and include no convolution operation. Therefore, the calculation load due to the updating process of the filter coefficients $C0^\wedge$ and $C1^\wedge$ can be reduced.

The control filter coefficient updating unit 42 updates the filter coefficients $W0$ and $W1$, based on the reference signals $r0$ and $r1$ and the second virtual error signal $e2$. The control filter coefficient updating unit 42 updates the filter coefficients $W0$ and $W1$, based on an LMS algorithm. The control filter coefficient updating unit 42 includes a first control filter coefficient updater 42a and a second control filter coefficient updater 42b.

The first control filter coefficient updater 42a and the second control filter coefficient updater 42b update the filter coefficients $W0$ and $W1$, based on the following equations, where $\mu4$ and $\mu5$ are step size parameters.

$$W0_{n+1} = W0_n - \mu4 \times e2_n \times r0_n$$

$$W1_{n+1} = W1_n - \mu5 \times e2_n \times r1_n$$

In the control filter coefficient updating unit 42, the filter coefficients $W0$ and $W1$ are repeatedly updated so as to

optimize the control filter W. In the active noise control device 100 using SAN filters, the updating formulae of the filter coefficients $W0$ and $W1$ are defined by four arithmetic operations and include no convolution operation. Therefore, the calculation load due to the updating process of the filter coefficients $W0$ and $W1$ can be reduced.

Improvements

10 The improvements of the present invention to the active noise control device 100 that uses the above method already proposed by the present inventors will be described.

15 FIG. 3 is a block diagram of the active noise control device 10 of the present embodiment. The active noise control device 10 of the present embodiment includes the active noise control device 100 that uses the method already proposed by the present inventors, as a signal processing unit 54. The active noise control device 10 further includes an initial value table 56, an updated value table 58, a result value table 60, an initial value table operating unit 62, an updated value table operating unit 64, a result value table operating unit 66, and an abnormality determination unit 68.

20 The active noise control device 10 has an arithmetic processing unit and a storage (not shown). The arithmetic processing unit includes, for example, a processor such as a central processing unit (CPU), a microprocessing unit (MPU), and memory devices of non-transitory or transitory tangible computer-readable recording media such as ROM or RAM. The storage is, for example, a non-transitory tangible computer-readable recording medium such as a hard disk or flash memory.

25 The initial value table 56 is a table-format memory area provided in a ROM, and the initial values of the filter coefficients $C0^\wedge$ and $C1^\wedge$ of the secondary path filter $C^\wedge$ described later are stored therein. The updated value table 58 is a table-format memory area provided in a RAM, and the updated values of the filter coefficients $C0^\wedge$ and $C1^\wedge$ are stored therein. The result value table 60 is a table-format 30 memory area provided in a ROM, and the result values of the filter coefficients $C0^\wedge$ and $C1^\wedge$ are stored therein.

35 The initial value table operating unit 62 performs writing or the like of the initial values to the initial value table 56. The updated value table operating unit 64 performs writing 45 or the like of the updated values to the updated value table 58. The result value table operating unit 66 performs writing or the like of the result values to the result value table 60. When the active noise control ends, the abnormality determination unit 68 determines whether an abnormality or 50 divergence has occurred in the active noise control. The abnormality determination unit 68 corresponds to the determination unit of the present invention.

40 The signal processing unit 54, the initial value table operating unit 62, the updated value table operating unit 64, 55 the result value table operating unit 66, and the abnormality determination unit 68 are realized by the arithmetic processing implemented by the arithmetic processing unit according to programs stored in the storage.

50 The updating process on the filter coefficients $C0^\wedge$ and $C1^\wedge$ in the secondary path filter coefficient updating unit 40 of the present embodiment partially differs from the updating process on the filter coefficients $C0^\wedge$ and $C1^\wedge$ in the secondary path filter coefficient updating unit 40 of the above-described active noise control device 100.

55 In the secondary path filter coefficient updating unit 40 of the active noise control device 100 that uses the method already proposed, the following equations are used to update

the filter coefficients $C0^\wedge$ and $C1^\wedge$, in the first secondary path filter coefficient update 40a and the second secondary path filter coefficient update 40b.

$$C0^\wedge_{n+1} = C0^\wedge_n - \mu_2 \times e1_n \times u0_n$$

$$C1^\wedge_{n+1} = C1^\wedge_n - \mu_3 \times e1_n \times u1_n$$

On the other hand, in the secondary path filter coefficient updating unit 40 of the active noise control device 10 (the signal processing unit 54) of the present embodiment, the filter coefficients $C0^\wedge$ and $C1^\wedge$ are updated based on the following equations, in the first secondary path filter coefficient update 40a and the second secondary path filter coefficient update 40b.

$$C0^\wedge(f)_{n+1} = C0^\wedge(f)_u - \mu_2 \times e1_n \times u0_n$$

$$C1^\wedge(f)_{n+1} = C1^\wedge(f)_u - \mu_3 \times e1_n \times u1_n$$

The updated values corresponding to the respective control target frequencies f stored in the updated value table 58 are input into the coefficients $C0^\wedge(f)_u$ and $C1^\wedge(f)_u$ in the above equation. Hereinafter, the first term on the right side of each of the updating formulae of the filter coefficients $C0^\wedge$ and $C1^\wedge$ may be referred to as a previous value.

In the method already proposed, the updated filter coefficients $C0^\wedge_n$ and $C1^\wedge_n$, updated in the previous time (time step n), are used as the previous values for the updating formulae. That is, even when the control target frequency f changes in a period from the previous updating (in time step n) to the current updating (in time step $n+1$), the previously updated filter coefficients $C0^\wedge_n$ and $C1^\wedge_n$ are used as the previous values for the updating formulae.

On the other hand, in the present embodiment, as the previous values for the updating formulae, the updated values corresponding to the control target frequency f at the time of the current updating (in time step $n+1$) are used. That is, the filter coefficients $C0^\wedge(f)_u$ and $C1^\wedge(f)_u$ that have been updated latest for the control target frequency f are used as the previous values for the updating formulae. That is, the previous values are not necessarily those that were updated at the previous time (in time step n).

Further, the secondary path filter coefficient updating unit 40 copies the updated filter coefficients $C0^\wedge$ and $C1^\wedge$ to the third secondary path filter 34a, the fourth secondary path filter 34b, the fifth secondary path filter 34c, and the sixth secondary path filter 34d in the reference signal generation unit 34.

Updating of Coefficients of Secondary Path Filter

FIG. 4 is a diagram for explaining the updating of the filter coefficients $C0^\wedge$ and $C1^\wedge$. As shown in FIG. 4, the initial value table 56 stores the initial values $C0^\wedge(f)_i$ and $C1^\wedge(f)_i$, in a table format, in association with a frequency. The updated value table 58 stores the updated values $C0^\wedge(f)_u$ and $C1^\wedge(f)_u$, in a table format, in association with the frequency. Further, the result value table 60 stores the result values $C0^\wedge(f)_r$ and $C1^\wedge(f)_r$ in a table format in association with the frequency.

The initial values corresponding to each frequency stored in the initial value table 56 are set to any of the following (i) to (v):

- (i) measurement values of the secondary path transfer characteristic C at each frequency;
- (ii) phase information of the measurement values of the secondary path transfer characteristic C at each frequency;

(iii) estimated values of the secondary path transfer characteristic C obtained by interpolation from the measurement values of the secondary path transfer characteristic C at typical frequencies, or phase information of the estimated values of the secondary path transfer characteristic C ;

(iv) estimated values of the secondary path transfer characteristic C estimated by the following equations:

$$C0^\wedge(f) = a(f) \times \cos(-2\pi f T)$$

$$C1^\wedge(f) = a(f) \times \sin(-2\pi f T)$$

where T is the time from when sound is emitted from the speaker 16 to when the sound reaches the microphone 22, and a is the amplitude constant; and

(v) convenient small values (when the initial values are not particularly set for convenience such as for system setting efficiency or the like).

FIG. 5 is a flowchart showing the flow of an updating process of the filter coefficients $C0^\wedge$ and $C1^\wedge$. The updating process of the filter coefficients $C0^\wedge$ and $C1^\wedge$ is executed every time the active noise control is performed.

At step S1, the updated value table operating unit 64 writes the initial values corresponding to each frequency in the initial value table 56 as the updated values corresponding to each frequency in the updated value table 58 ((A) in FIG. 4), then the process proceeds to step S2.

At step S2, the frequency detection circuit 26a of the signal processing unit 54 detects the control target frequency f , and the process proceeds to step S3.

At step S3, the secondary path filter coefficient updating unit 40 reads the updated values corresponding to the control target frequency f as the previous values ((B) in FIG. 4), and the process proceeds to step S4.

At step S4, the secondary path filter coefficient updating unit 40 updates the filter coefficients $C0^\wedge$ and $C1^\wedge$, and the process proceeds to step S5.

At step S5, the updated value table operating unit 64 writes the updated filter coefficients $C0^\wedge$ and $C1^\wedge$ as the updated values corresponding to the control target frequency f ((C) in FIG. 4), and the process proceeds to step S6.

At step S6, the abnormality determination unit 68 determines whether or not the active noise control has been ended. The active noise control ends when the engine 18 stops, when an abnormality has occurred in the active noise control, or when divergence has occurred in the active noise control. When the active noise control is not ended, the process returns to step S2. When the active noise control has been ended, the process proceeds to step S7.

At step S7, the abnormality determination unit 68 determines whether or not the active noise control has ended normally. When it is determined that the active noise control has ended normally, the process proceeds to step S8. When it is determined that the active noise control has not ended normally due to an abnormality or divergence of the active noise control, the process proceeds to step S10.

At step S8, the initial value table operating unit 62 determines whether or not rewriting of the initial values of the initial value table 56 is permitted. When rewriting of the initial value table 56 is permitted, the process proceeds to step S9. When rewriting of the initial value table 56 is not permitted, the updating process of the filter coefficients $C0^\wedge$ and $C1^\wedge$ is terminated.

At step S9, the initial value table operating unit 62 rewrites the initial values corresponding to each frequency in the initial value table 56 with the updated values corre-

11

sponding to the frequency in the updated value table 58 ((D) in FIG. 4), and the updating process of the filter coefficients $C0^\wedge$ and $C1^\wedge$ is terminated.

At step S10, the result value table operating unit 66 writes the updated values corresponding to each frequency of the updated value table 58, as the result values corresponding to the frequency, into the result value table 60 ((E) in FIG. 4), and the updating process of the filter coefficients $C0^\wedge$ and $C1^\wedge$ is terminated.

The initial value table 56 and the result value table 60 can be copied to a personal computer or the like connected to the vehicle 12. Therefore, when an abnormality or divergence occurs in the active noise control, it is possible to investigate and verify the cause of the occurrence of the abnormality or divergence in the active noise control by comparing the updated values stored in the initial value table 56 with the result values stored in the result value table 60.

Experimental Result

The present inventors conducted experiments on noise reduction performance of active noise control. The experimental results will be shown below. Each of the following experiments was performed under a secondary path transfer characteristic C having a gain characteristic shown by the thin line in FIG. 6A and a phase characteristic shown by the thin line in FIG. 6B.

Experiment (1)

In experiment (1), the sound pressure level of the noise in the vehicle passenger compartment 14 is measured when the vehicle 12 is accelerated from the stopped state while active noise control is off.

Experiment (2)

In experiment (2), the sound pressure level of the noise in the vehicle passenger compartment 14 is measured when the vehicle 12 is accelerated from the stopped state while active noise control is being performed by the active noise control device 100 that uses the method already proposed by the present inventors.

Experiment (3)

In experiment (3), the sound pressure level of the noise in the vehicle passenger compartment 14 is measured when the vehicle 12 is accelerated from the stopped state while active noise control is being performed by the active noise control device 10 of the present embodiment. In experiment (3), the initial values at each frequency in the initial value table 56 are set to the measured values of the secondary path transfer characteristic C of the frequency.

Experiment (4)

In experiment (4), the sound pressure level of the noise in the vehicle passenger compartment 14 is measured when the vehicle 12 is accelerated from the stopped state while active noise control is being performed by the active noise control device 10 of the present embodiment. In experiment (4), the initial values at each frequency in the initial value table 56 is set to the estimated values of the secondary path transfer characteristic C estimated by the following equations.

$$C0^\wedge(f) = \cos(-2\pi f T)$$

$$C1^\wedge(f) = \sin(-2\pi f T)$$

12

where T is set to 0.01 seconds. The gain characteristic and phase characteristic of the estimated values of the secondary path transfer characteristic C are shown by the thick lines in FIGS. 6A and 6B.

Comparison of Results of Experiments (1) to (3)

FIG. 7 is a graph showing the sound pressure levels of the noise in the vehicle passenger compartment 14, measured in the experiments (1) to (3).

As shown in FIG. 7, at the start of driving the vehicle 12 (at the engine speed of 1600 RPM to 2000 RPM), the noise reduction performance in experiment (3) is higher than that in experiment (2) by 10 dB or more. In particular, at the time right after the start of driving the vehicle 12 (at the engine speed of around 1600 RPM), the noise was not reduced in experiment (2), whereas the noise was reduced by about 10 dB in experiment (3).

Comparison of Results of Experiments (1), (2) and (4)

FIG. 8 is a graph showing the sound pressure level of the noise in the vehicle passenger compartment 14, measured in the experiments (1), (2) and (4).

As shown in FIG. 8, even when an accurate estimate of the secondary path transfer characteristic C cannot be obtained as in experiment (4), the noise reduction performance in experiment (4) is about the same as or higher than that of experiment (2), in the engine speed range of 4500 RPM or lower. The noise reduction performance in the engine speed range exceeding 4500 RPM, the noise reduction performance in experiment (4) is lower than that in experiment (2). This is because, as shown in FIGS. 6A and 6B, the estimate of the secondary path transfer characteristic C deviates from the actual secondary path transfer characteristic C in the range where the frequency exceeds 150 Hz, which corresponds to the engine speed of 4500 RPM. However, by repeating the updating of the filter coefficients $C0^\wedge$ and $C1^\wedge$, the secondary path filter C approaches the secondary path transfer characteristic C, so that the noise reduction performance is improved.

Experiment (5)

In experiment (5), the sound pressure level of the noise in the vehicle passenger compartment 14 is measured during the first driving when the vehicle 12 is accelerated from the stopped state while active noise control is being performed by the active noise control device 10 of the present embodiment. In experiment (5), the initial values at each frequency in the initial value table 56 are set to convenient small values.

Experiment (6)

In experiment (6), the sound pressure level of the noise in the vehicle passenger compartment 14 is measured during the third driving when the vehicle 12 is accelerated from the stopped state while active noise control is being performed by the active noise control device 10 of the present embodiment. In experiment (6), the initial values at each frequency in the initial value table 56 are set to convenient small values.

13

Comparison of Results of Experiments (1), (5) and (6)

FIG. 9 is a graph showing the sound pressure levels of the noise in the vehicle passenger compartment 14, measured in the experiments (1), (5) and (6).

As shown in FIG. 9, the sound pressure level during the first driving in experiment (5) exceeds, in part, the sound pressure level in experiment (1) in which active noise control is off. However, as in experiment (6), the noise reduction performance is improved even with a relatively small number of updates of the filter coefficients $C0^\wedge$ and $C1^\wedge$, or during the third driving.

FIG. 10 shows the phase characteristic of the secondary path transfer characteristic C, the phase characteristic of the updated value after the end of the first driving in experiment (5), and the phase characteristic of the updated value after the end of the third driving in experiment (6).

As shown in FIG. 10, there is a tendency that random errors, which are large with the updated values after the end of the first driving, converge toward the secondary path transfer characteristic C with the updated values after the end of the third driving. Since the secondary path filter coefficient updating unit 40 rewrites the initial values in the initial value table 56 with the updated filter coefficients $C0^\wedge$ and $C1^\wedge$, it is possible to update the filter coefficients $C0^\wedge$ and $C1^\wedge$ with the highly accurate initial values at the next start of active noise control. Therefore, it is possible to improve the noise reduction performance by the active noise control.

Operation and Effect

In the active noise control device 10 of the present embodiment, the initial value table 56 stores the initial values $C0^\wedge(f)_i$ and $C1^\wedge(f)_i$ in association with the frequency, in a table format. The initial values corresponding to each frequency stored in the initial value table 56 is set to any of the following (i) to (v):

- (i) measurement values of the secondary path transfer characteristic C at each frequency;
- (ii) phase information of the measurement values of the secondary path transfer characteristic C at each frequency;
- (iii) estimated values of the secondary path transfer characteristic C obtained by interpolation based on the measurement values of the secondary path transfer characteristic C at typical frequencies, or phase information of the estimated values of the secondary path transfer characteristic C;
- (iv) the estimated values of the secondary path transfer characteristic C estimated by the following equations:

$$C0^\wedge(f) = a(f) \times \cos(-2\pi f T)$$

$$C1^\wedge(f) = a(f) \times \sin(-2\pi f T)$$

where T is the time from when sound is emitted from the speaker 16 to when the sound reaches the microphone 22, and a is the amplitude constant; and

(v) convenient small values (when the initial values are not particularly set for convenience such as for system setting efficiency or the like).

Further, the updated value table operating unit 64 writes the initial values corresponding to the control target frequency f in the initial value table 56 to the updated values corresponding to the control target frequency f in the updated value table 58 at the start of active noise control. The secondary path filter coefficient updating unit 40 reads the updated values corresponding to the control target frequency f from the updated value table 58 before updating the

14

filter coefficients $C0^\wedge$ and $C1^\wedge$. Then, the secondary path filter coefficient updating unit 40 updates the filter coefficients $C0^\wedge$ and $C1^\wedge$ by using the read updated values as the previous values. The updated value table operating unit 64 writes the updated filter coefficients $C0^\wedge$ and $C1^\wedge$ to the updated values corresponding to the control target frequency f in the updated value table 58. Provision of the initial value table 56 and the updated value table 58 enables the active noise control device 10 to set the initial values of the filter coefficients $C0^\wedge$ and $C1^\wedge$ for each frequency, and also update the filter coefficients $C0^\wedge$ and $C1^\wedge$ for each frequency. With such a configuration, the active noise control device 10 can significantly improve the initial noise reduction performance, especially after the start of active noise control.

Further, in the active noise control device 10 of the present embodiment, when the abnormality determination unit 68 determines that the active noise control has ended without abnormality or divergence, the initial value table operating unit 62 rewrites the initial values in the initial value table 56 with the updated values of the updated value table 58. With such a configuration, at the next start of active noise control, the filter coefficients $C0^\wedge$ and $C1^\wedge$ can be updated using highly accurate initial values, whereby it is possible to improve the noise reduction performance of the active noise control.

Further, in the active noise control device 10 of the present embodiment, when the abnormality determination unit 68 determines that the active noise control has ended with abnormality or divergence, the initial value table operating unit 62 does not rewrite the initial values of the initial value table 56 with the updated values of the updated value table 58. With such a configuration, at the next active noise control, the filter coefficients $C0^\wedge$ and $C1^\wedge$ at the time when abnormality or divergence occurred in the active noise control are not written as the updated values in the updated value table 58, so that the active noise control can be returned to normal.

Further, in the active noise control device 10 of the present embodiment, when the abnormality determination unit 68 determines that the active noise control has ended with abnormality or divergence, the result value table operating unit 66 rewrites the result values in the result value table 60 with the updated values of the updated value table 58. With such a configuration, when an abnormality or divergence occurs in the active noise control, it is possible to investigate and verify the cause of the occurrence of the abnormality or divergence in the active noise control by comparing the updated values stored in the initial value table 56 with the result values stored in the result value table 60.

50

Second Embodiment

In the active noise control device 10 of this embodiment, the filter coefficients $C0^\wedge$ and $C1^\wedge$ updated based on the updating formulae in the secondary path filter coefficient updating unit 40 and the updated values stored in the updated value table 58 are subjected to weighted averaging.

The first secondary path filter coefficient updater 40a and the second secondary path filter coefficient updater 40b perform weighted averaging of the filter coefficients $C0^\wedge$ and $C1^\wedge$ based on the following equations. In the equations, L is the frequency range for weighted averaging, and θ is a weight coefficient.

$$C0^\wedge(f)_{n+1} = \sum_{i=f-L}^{f+L} \theta(i) \times C0^\wedge(i) \_u$$

$$C1^\wedge(f)_{n+1} = \sum_{i=f-L}^{f+L} \theta(i) \times C1^\wedge(i) \_u$$

The weight coefficient θ is defined based on the following equation.

$$\text{If } i = f, \theta(f) = \beta, \text{ else } \theta(i) = \frac{1 - \beta}{2L}$$

Random Error Reduction Principle

By repeating the updating of the filter coefficients $C0^\wedge$ and $C1^\wedge$, the random error of the secondary path filter C becomes small, and the noise reduction performance by active noise control is improved. In the present embodiment, the weighted averaging is performed on the filter coefficients $C0^\wedge$ and $C1^\wedge$ updated based on the updating formulae and the updated values stored in the updated value table 58, whereby it is possible to reduce the random error of the secondary path filter C with a small number of updates.

The filter coefficients $C0^\wedge$ and $C1^\wedge$ are represented by the following formulae in a combination of a true value and errors.

$$C0^\wedge(f)_n = E[C0^\wedge(f)] + \sigma0(f)_n + \delta0(f)_n$$

$$C1^\wedge(f)_n = E[C1^\wedge(f)] + \sigma1(f)_n + \delta1(f)_n$$

where $E[C0^\wedge(f)]$ is the expected value of $C0^\wedge$, $E[C1^\wedge(f)]$ is the expected value of $C1^\wedge$, σ is a system error, and δ is a random error. The expected value $E[C0^\wedge(f)]$ and the expected value $E[C1^\wedge(f)]$ are values that do not vary with time.

Now, if the system error σ is omitted, the filter coefficient $C0^\wedge$ is rewritten as the following equation.

$$C0^\wedge(f)_{n+1} = \frac{1 - \beta}{2L} \sum_{i=f-L}^{f+L} (E[C0^\wedge(i)] + \delta0(i)_n) + \left(\beta - \frac{1 - \beta}{2L} \right) (E[C0^\wedge(f)] + \delta0(f)_n) - \beta \times \mu2 \times e1_n \times u0_n$$

When the frequency range L for weighted averaging is sufficiently large, the random error δ satisfies the following equation.

$$\sum_{i=f-L}^{f+L} \delta0(i)_n = 0$$

Therefore, the filter coefficient $C0^\wedge$ can be further rewritten into the following equation.

$$C0^\wedge(f)_{n+1} = E[C0^\wedge(f)] + \sigma M0(f) + \left(\beta - \frac{1 - \beta}{2L} \right) \delta0(f)_n - \beta \times \mu2 \times e1_n \times u0_n$$

$$\sigma M0(f) = \frac{1 - \beta}{2L} \sum_{i=f-L, i \neq f}^{f+L} E[C0^\wedge(i)] - (1 - \beta) E[C0^\wedge(f)]$$

where $\sigma M0$ is a system error caused by the averaging process, and the closer to 1 the value of β is, the smaller the magnitude of $\sigma M0$. The random error δ is represented by the following equation using the random error δ when the time step is $n=1$.

$$\delta0(f)_{n+1} = \left(\beta - \frac{1 - \beta}{2L} \right) \delta0(f)_n = \left(\beta - \frac{1 - \beta}{2L} \right)^n \delta0(f)_1$$

From this equation, it can be understood that by setting β so as to meet the inequality of $1/(2L) < \beta < 1$, the random error δ becomes smaller as the number of updates (time step n) increases. As the number of updates (time step n) increases, the random error δ converges to 0. As a result, the filter coefficient $C0^\wedge$ can be represented in a form with no random error δ , as shown in the following equation.

$$C0^\wedge(f)_{n+1} = E[C0^\wedge(f)]$$

Similarly, the filter coefficient $C1^\wedge$ can be represented in a form with no random error δ , as shown in the following equation that includes no random error δ .

$$C1^\wedge(f)_{n+1} = E[C1^\wedge(f)]$$

Experimental Result

The present inventors conducted experiments on noise reduction performance by active noise control. The experimental results are shown below. Each of the following experiments was performed under a secondary path transfer characteristic C having a gain characteristic shown by the thin line in FIG. 6A and a phase characteristic shown by the thin line in FIG. 6B.

Experiment (7)

In experiment (7), the sound pressure level of the noise in the vehicle passenger compartment 14 is measured during the third driving when the vehicle 12 is accelerated from the stopped state while active noise control is being performed by the active noise control device 10 of the present embodiment. In experiment (7), the initial values at each frequency in the initial value table 56 are set to convenient small values.

Comparison of Experiments (1), (6) and (7)

FIG. 11 is a graph showing the sound pressure levels of the noise in the vehicle passenger compartment 14, measured in the experiments (1), (6) and (7).

As shown in FIG. 11, in experiment (7), the noise reduction performance is improved at engine speed of 1800 to 2400 RPM by 10 dB or more as compared with experiment (6).

FIG. 12 shows the phase characteristic of a secondary path transfer characteristic C, the phase characteristic of the updated value after the end of the third driving in experiment (6), and the phase characteristic of the updated value after the end of the third driving in experiment (7). In experiment (7), the random error is greatly reduced as compared with experiment (6) at the frequency of 60 to 80 Hz, which corresponds to the engine speed of 1800 to 2400 RPM.

In each of experiments (6) and (7), driving was performed three times. It can be understood from FIGS. 11 and 12 that the updated values in experiment (7) converged to the secondary path transfer characteristic C earlier compared to experiment (6).

Operation and Effect

In the active noise control device 10 of the present embodiment, the secondary path filter coefficient updating unit 40 performs weighted averaging of the filter coefficients $C0^\wedge$ and $C1^\wedge$ updated based on the updating formulae and the updated values stored in the updated value table 58. This enables the random error of the secondary path filter C to

converge early, and thus it is possible to improve the noise reduction performance of the active noise control.

Third Embodiment

In the active noise control device 10 of this embodiment, the filter coefficients $C0^\wedge$ and $C1^\wedge$ are updated based on the following respective equations, in the first secondary path filter coefficient updater 40a and the second secondary path filter coefficient updater 40b of the secondary path filter coefficient updating unit 40.

$$C0^\wedge(f)_{n+1} = [\gamma \times C0^\wedge_n + (1-\gamma) \times C0^\wedge(f)_{-n}] - \mu_2 \times e_{1,n} \times u_{0,n}$$

$$C1^\wedge(f)_{n+1} = [\gamma \times C1^\wedge_n + (1-\gamma) \times C1^\wedge(f)_{-n}] - \mu_3 \times e_{1,n} \times u_{1,n}$$

where $C0^\wedge_n$ and $C1^\wedge_n$ are variables for holding the update results of the filter coefficients $C0^\wedge$ and $C1^\wedge$ of the previous time (time step n). $C0^\wedge_1$ and $C1^\wedge_1$, which are the initial values of the variables $C0^\wedge_n$ and $C1^\wedge_n$, are set at values as small as 0. γ is a coefficient that satisfies $0 \leq \gamma \leq 1$.

FIG. 13 is a diagram showing the phase characteristic of the updated values stored in the updated value table 58 and the phase characteristic of a secondary path transfer characteristic C. The engine speed that is often used in normal driving is 3600 RPM or lower, and the frequency of the noise arising at that time is 120 Hz or lower. Therefore, in the frequency range of 120 Hz or lower, the filter coefficients $C0^\wedge$ and $C1^\wedge$ are updated repeatedly, so that the phase characteristic of the updated values substantially converges to the secondary path transfer characteristic C.

On the other hand, a range of the engine speed of higher than 3600 RPM is used for the driving in limited situations such as when the vehicle is accelerated to join from a ramp to a highway, or when climbing a steep uphill. Therefore, even when the active noise control has been continued for a certain period of time, the filter coefficients $C0^\wedge$ and $C1^\wedge$ are not updated in the range where the frequency is higher than 120 Hz, and the updated values remain equal to the initial values. Or, the filter coefficients $C0^\wedge$ and $C1^\wedge$ are not updated sufficiently, so that the secondary path filter C remains deviated from the secondary path transfer characteristic C. Therefore, when the engine speed exceeds 3600 RPM, the noise reduction performance by active noise control deteriorates, and the engine noise may suddenly increase.

Since the control target frequency f changes continuously with the passage of time, the control target frequency f of the previous time (time step n) is often a frequency near the control target frequency f of the current time (time step n+1). Further, since the secondary path transfer characteristic C changes continuously according to the control target frequency f, the secondary path transfer characteristic C in the previous time (time step n) and the secondary path transfer characteristic in the current time (time step n+1) C have similar characteristics.

Under consideration of the above fact, the filter coefficients $C0^\wedge$ and $C1^\wedge$ updated in the previous time (time step n) and the updated values corresponding to the control target frequency f of the current time (time step n+1) in the updated value table 58 are added at a predetermined ratio, and the resultant values are used as the previous values for the updating formulae to update the filter coefficients $C0^\wedge$ and $C1^\wedge$.

Note that the coefficient γ may be provided for each frequency, and the coefficient γ may be attenuated according to the following equation as the number of updates of the filter coefficients $C0^\wedge$ and $C1^\wedge$ increases.

$$\gamma(f)_{n+1} = \gamma(f)_n \times \text{Coef}_d$$

where Coef_d is an attenuation coefficient that is a positive number smaller than 1. In this case, the initial value of γ may be set to 1 or a value close to 1.

When the filter coefficients $C0^\wedge$ and $C1^\wedge$ for the control target frequency f are updated for the first time, γ takes a value close to 1. Therefore, since the filter coefficients $C0^\wedge$ and $C1^\wedge$ are updated mainly based on the previously updated filter coefficients $C0^\wedge$ and $C1^\wedge$, it is possible to suppress deterioration of the noise reduction performance of the active noise control.

As the filter coefficients $C0^\wedge$ and $C1^\wedge$ at the control target frequency f are updated more frequently, γ is attenuated to 0. Therefore, since the filter coefficients $C0^\wedge$ and $C1^\wedge$ are updated mainly based on the updated values in the updated value table 58, the noise reduction performance of active noise control can be improved.

Further, a minimum value may be set for the coefficient γ .

$$\text{If } \gamma(f)_{n+1} < \gamma_{min}, \text{ Then } \gamma(f)_{n+1} = \gamma_{min}$$

Setting the minimum value for the coefficient γ allows the updating of the filter coefficients $C0^\wedge$ and $C1^\wedge$ to always involve the components of the previously updated filter coefficients $C0^\wedge$ and $C1^\wedge$. Therefore, even if the secondary path transfer characteristic C abruptly changes during active noise control, the noise reduction performance can be restored by active noise control at an early stage.

Experimental Result

The present inventors conducted experiments on noise reduction performance of active noise control. The experimental results will be shown below. Each of the following experiments was performed under a secondary path transfer characteristic C having a gain characteristic shown by a thin line in FIG. 6A and a phase characteristic shown by a thin line in FIG. 6B.

Experiment (8)

In experiment (8), the sound pressure level of the noise in the vehicle passenger compartment 14 is measured during the first driving when the vehicle 12 is accelerated from the stopped state while active noise control is being performed by the active noise control device 10 of the present embodiment. In experiment (8), the initial values at each frequency in the initial value table 56 are set to convenient, small values. In experiment (8), γ is set to 0.5 ($\gamma=0.5$).

Experiment (9)

In experiment (9), the sound pressure level of the noise in the vehicle passenger compartment 14 is measured during the third driving when the vehicle 12 is accelerated from the stopped state while active noise control is being performed by the active noise control device 10 of the present embodiment. In experiment (9), the initial values at each frequency in the initial value table 56 are set to convenient, small values. In experiment (9), γ is set to 0.5 ($\gamma=0.5$).

Contrast of Experiments (1), (5), (8)

FIG. 14 is a graph showing the sound pressure levels of the noise in the vehicle passenger compartment 14, measured in the experiments (1), (5) and (8).

As shown in FIG. 14, at the time right after the start of driving the vehicle 12 at the engine speed of around 1600 RPM, the noise was hardly reduced in experiment (8), but

19

after that, the noise reduction performance in experiment (8) was improved compared to experiment (5).

Comparison of Experiments (1), (6) and (9)

FIG. 15 is a graph showing the sound pressure levels of the noise in the vehicle passenger compartment 14, measured in the experiments (1), (6) and (9). When the number of drives reaches three times, in experiment (9) improvement in the reduction of the noise at around the engine speed of 1600 RPM right after the start of driving the vehicle 12 could be realized.

Operation and Effect

In the active noise control device 10 of the present embodiment, the secondary path filter coefficient updating unit 40 updates the current filter coefficients C^* , by using, as the previous values, the values obtained by adding the previously updated filter coefficients of the secondary path filter C^* and the updated values read from the updated value table 58 at a predetermined ratio. With such a configuration, even when the accuracy of the updated values in the updated value table 58 is not high, the noise reduction performance of active noise control can be improved.

Fourth Embodiment

In this embodiment, the level of the anti-noise sound output from the speaker 16 is prevented from becoming excessive. Five methods 1 to 5 are shown below as signal processing methods for suppressing excessive loudness of the anti-noise sound output from the speaker 16.

Method 1

FIG. 16 is a block diagram of a signal processing unit 54. As shown in FIG. 16, a multiplier 70 for multiplying the apparent magnitude of the second estimated anti-noise signal $y2^*$ input to the adder 52 by $(1+\alpha)$ is added to that of the block diagram of FIG. 2. This increases the apparent magnitude of the second estimated anti-noise signal $y2^*$ by $(1+\alpha)$ times, so that the size of the control filter W can be suppressed.

Method 2

FIG. 17 is a block diagram of a signal processing unit 54. As shown in FIG. 17, a multiplier 72 for multiplying the apparent magnitude of the estimated noise signal d^* input to the adder 52 by $(1-\alpha)$ is added to that of the block diagram of FIG. 2. This reduces the apparent magnitude of the estimated noise signal d^* by $(1-\alpha)$ times, so that the size of the control filter W can be suppressed.

Method 3

FIG. 18 is a block diagram of a signal processing unit 54. As shown in FIG. 18, a multiplier 74 for multiplying the apparent magnitude of the first estimated anti-noise signal $y1^*$ input to the adder 46 by $(1-\alpha)$ is added to that of the block diagram of FIG. 2.

Method 4

FIG. 19 is a block diagram of a signal processing unit 54 to which a method 4 is applied. As shown in FIG. 19, a

20

multiplier 76 for multiplying the apparent magnitude of the estimated noise signal d^* input to the adder 46 by $(1+\alpha)$ is added to that of the block diagram of FIG. 2.

Method 5

FIG. 20 is a block diagram of a signal processing unit 54. As shown in FIG. 20, a filter 78 for multiplying the apparent magnitude of the second estimated anti-noise signal $y2^*$ input to the adder 52 by $(1+\alpha)$ is added to that of the block diagram of FIG. 2. The filter coefficient, designated at α , of the filter 78 is updated by a filter coefficient updating unit 80.

In method 5, the minimum value α_{min} is set for the filter coefficient α . The filter coefficient α satisfies the following equation.

If $\alpha_n < \alpha_{min}$, Then $\alpha_n = \alpha_{min}$

When the secondary path transfer characteristic C changes significantly, such as when the backrest of the seat 20 is tilted back, the difference between the updated values in the updated value table 58 and the secondary path transfer characteristic C becomes large. In the active noise control of the present embodiment, the coefficients $C0^*$ and $C1^*$ of the secondary path filter C^* change following the change of the secondary path transfer characteristic C. Therefore, the sound pressure level of the anti-noise sound output from the speaker 16 may suddenly change, thereby causing the occupant to feel discomfort. By updating the filter coefficient α in a range greater than the minimum value α_{min} by the filter coefficient updating unit 80, it is possible to prevent excessive loudness of the anti-noise sound output from the speaker 16 during the transitional state in which the change of the secondary path transfer characteristic C is followed. Thus, it is possible to alleviate the feeling of discomfort for the occupant.

Experimental Result

The present inventors conducted experiments on noise reduction performance of active noise control. The experimental results will be shown below. Each of the following experiments was performed under a secondary path transfer characteristic C having a gain characteristic shown by a thin line in FIG. 6A and a phase characteristic shown by a thin line in FIG. 6B.

Experiment (10)

In experiment (10), the amplitude of the control filter W is measured when the vehicle 12 is accelerated from the stopped state while active noise control is being performed by the active noise control device 10 of the present embodiment. Further, in experiment (10), the sound pressure level of the noise in the vehicle passenger compartment 14 is measured when the vehicle 12 is on. In experiment (10), α was set equal to 0 ($\alpha=0$) in the above method 1. In experiment (10), the initial values at each frequency in the initial value table 56 is set to the measurement values of the secondary path transfer characteristic C at each frequency shown by the thin lines in FIGS. 6A and 6B.

Experiment (11)

In experiment (11), the amplitude of the control filter W is measured when the vehicle 12 is accelerated from the stopped state while active noise control is being performed by the active noise control device 10 of the present embodiment.

ment. Further, in experiment (11), the sound pressure level of the noise in the vehicle passenger compartment **14** is measured when the vehicle **12** is on. In experiment (11), α was set equal to 0.25 ($\alpha=0.25$) in the above method 1. In experiment (11), the initial values at each frequency in the initial value table **56** is set to the measurement values of the secondary path transfer characteristic C at each frequency shown by the thin lines in FIGS. **6A** and **6B**.

Comparison of Results of Experiments (10) and (11)

FIG. **21** is a graph showing the amplitudes of the control filter W, measured in the experiments (10) and (11). As shown in FIG. **21**, the level of the amplitude of the control filter W is reduced in experiment (11) in which $\alpha=0.25$ as compared to experiment (10) in which $\alpha=0$.

Comparison of Experiments (1), (10) and (11)

FIG. **22** is a graph showing the sound pressure levels of the noise in the vehicle passenger compartment **14**, measured in the experiments (1), (10) and (11). As shown in FIG. **22**, it can be seen that the noise reduction performance is improved in experiment (11) in which $\alpha=0.25$, as compared to experiment (10) in which $\alpha=0$.

Operation and Effect

In the active noise control device **10** of the present embodiment, the signal processing unit **54** includes the multiplier **70** that adjusts and increases the magnitude of the second estimated anti-noise signal $y2^*$ used to generate the second virtual error signal $e2$, the multiplier **72** that adjusts and reduces the magnitude of the estimated noise signal d^* used to generate the second virtual error signal $e2$, the multiplier **74** that adjusts and reduces the magnitude of the first estimated anti-noise signal $y1^*$ used to generate the first virtual error signal $e1$, or the multiplier **76** that adjusts and increases the magnitude of the estimated noise signal d^* used to generate the first virtual error signal $e1$. With this configuration, it is possible to prevent excessive loudness of the anti-noise sound output from the speaker **16**.

Technical Idea Obtained from Embodiments

The technical ideas that can be grasped from the above embodiments are described below.

An active noise control device **(10)** performs active noise control for controlling a speaker **(16)** based on an error signal that changes in accordance with the combined sound of a noise transmitted from a vibration source and an anti-noise sound for cancelling the noise, output from the speaker, the active noise control device including: a standard signal generation unit **(26)** configured to generate a standard signal in accordance with a control target frequency; a control signal generation unit **(28)** configured to generate a control signal for controlling the speaker by signal-processing the standard signal through a control filter that is an adaptive notch filter; an estimated noise signal generation unit **(32)** configured to generate an estimated noise signal by signal-processing the standard signal through a primary path filter that is an adaptive notch filter; a first estimated anti-noise signal generation unit **(30)** configured to generate a first estimated anti-noise signal by signal-processing the control signal through a secondary path filter that is an adaptive notch filter; a reference signal generation unit **(34)**

configured to generate a reference signal by signal-processing the standard signal through the secondary path filter; a second estimated anti-noise signal generation unit **(36)** configured to generate a second estimated anti-noise signal by signal-processing the reference signal through the control filter; a first virtual error signal generation unit **(46)** configured to generate a first virtual error signal from the error signal, the first estimated anti-noise signal, and the estimated noise signal; a second virtual error signal generation unit **(52)** configured to generate a second virtual error signal from the second estimated anti-noise signal and the estimated noise signal; a secondary path filter coefficient updating unit **(40)** configured to successively and adaptively update the coefficients of the secondary path filter so as to minimize the magnitude of the first virtual error signal, based on the control signal and the first virtual error signal; a control filter coefficient updating unit **(42)** configured to successively and adaptively update the coefficients of the control filter so as to minimize the magnitude of the second virtual error signal, based on the reference signal and the second virtual error signal; an initial value table **(56)** configured to store initial values of the coefficients of the secondary path filter in association with a frequency, in a table format; an updated value table **(58)** configured to store updated values of the coefficients of the secondary path filter in association with the frequency, in a table format; an updated value table operating unit **(64)** configured to write the initial values of the initial value table into the updated value table as the updated values at the start of the active noise control and write the coefficients of the secondary path filter updated by the secondary path filter coefficient updating unit during the active noise control, into the updated value table as the updated values. The secondary path filter coefficient updating unit is configured to read the updated values corresponding to the frequency from the updated value table before updating the coefficients of the secondary path filter, and update the coefficients of the secondary path filter, using the read updated values as the previous values.

The above active noise control device may include a primary path filter coefficient updating unit **(38)** configured to successively and adaptively update the coefficients of the primary path filter so as to minimize the magnitude of the first virtual error signal, based on the standard signal and the first virtual error signal.

The above active noise control device may include an initial value table operating unit **(62)** configured to rewrite the initial values in the initial value table with the updated values of the updated value table at the end of the active noise control.

The above active noise control device may include a determination unit **(68)** configured to determine whether an abnormality or divergence has occurred in the active noise control, at the end of the active noise control, and the initial value table operating unit may be configured not to rewrite the initial values in the initial value table with the updated values of the updated value table when the determination unit determines that an abnormality or divergence has occurred in the active noise control.

In the above active noise control device, the secondary path filter coefficient updating unit may be configured to perform weighted averaging of the coefficients of the secondary path filter updated according to updating formulae and the updated values in the updated value table.

In the above active noise control device, the secondary path filter coefficient updating unit may be configured to update the coefficients of the secondary path filter, by using, as the previous values, the values obtained by adding the

coefficients of the secondary path filter after the previous updating in the secondary path filter coefficient updating unit and the read updated values at a predetermined ratio.

The above active noise control device may include a determination unit configured to determine whether an abnormality or divergence has occurred in the active noise control, at the end of the active noise control, a result value table (60) configured to store the result values of the coefficients of the secondary path filter in association with the frequency, in a table format, and a result value table operating unit (66) configured to rewrite the result values in the result value table with the updated values of the updated value table when the determination unit determines an abnormality or divergence has occurred in the active noise control.

The above active noise control device may include a multiplier (70, 72, 74, 76) which makes an adjustment so as to increase the magnitude of the second estimated anti-noise signal used for generation of the second virtual error signal, which makes an adjustment so as to reduce the magnitude of the estimated noise signal used for generation of the second virtual error signal, which makes an adjustment so as to reduce the magnitude of the first estimated anti-noise signal used for generation of the first virtual error signal, or which makes an adjustment so as to increase the magnitude of the estimated noise signal used for generation of the first virtual error signal.

The present invention is not particularly limited to the embodiment described above, and various modifications are possible without departing from the essence and gist of the present invention.

What is claimed is:

1. An active noise control device that performs active noise control for controlling a speaker based on an error signal that changes in accordance with combined sound of a noise transmitted from a vibration source and an anti-noise sound for cancelling the noise, output from the speaker, the active noise control device comprising one or more processors that execute computer-executable instructions stored in a memory,

wherein the one or more processors execute the computer-executable instructions to cause the active noise control device to:

generate a standard signal in accordance with a control target frequency;

generate a control signal for controlling the speaker by signal-processing the standard signal through a control filter that is an adaptive notch filter;

generate an estimated noise signal by signal-processing the standard signal through a primary path filter that is an adaptive notch filter;

generate a first estimated anti-noise signal by signal-processing the control signal through a secondary path filter that is an adaptive notch filter;

generate a reference signal by signal-processing the standard signal through the secondary path filter;

generate a second estimated anti-noise signal by signal-processing the reference signal through the control filter;

generate a first virtual error signal from the error signal, the first estimated anti-noise signal, and the estimated noise signal;

generate a second virtual error signal from the second estimated anti-noise signal and the estimated noise signal;

successively and adaptively update a coefficient of the secondary path filter so as to minimize magnitude of

the first virtual error signal, based on the control signal and the first virtual error signal;

successively and adaptively update a coefficient of the control filter so as to minimize magnitude of the second virtual error signal, based on the reference signal and the second virtual error signal;

store initial values of the coefficient of the secondary path filter into an initial value table in association with a frequency, in a table format;

store updated values of the coefficient of the secondary path filter into an updated value table in association with the frequency, in a table format;

write the initial values of the initial value table into the updated value table as the updated values at start of the active noise control and write the coefficient of the secondary path filter updated during the active noise control, into the updated value table as the updated values; and

read the updated value corresponding to the frequency from the updated value table before updating the coefficient of the secondary path filter, and update the coefficient of the secondary path filter, using the read updated value as a previous value.

2. The active noise control device according to claim 1, wherein the one or more processors cause the active noise control device to successively and adaptively update a coefficient of the primary path filter so as to minimize the magnitude of the first virtual error signal, based on the standard signal and the first virtual error signal.

3. The active noise control device according to claim 1, wherein the one or more processors cause the active noise control device to rewrite the initial values in the initial value table with the updated values of the updated value table at end of the active noise control.

4. The active noise control device according to claim 3, wherein the one or more processors cause the active noise control device to:

determine whether an abnormality or divergence has occurred in the active noise control, at the end of the active noise control, and

not rewrite the initial values in the initial value table with the updated values of the updated value table when it is determined, in the determining, that an abnormality or divergence has occurred in the active noise control.

5. The active noise control device according to claim 1, wherein the one or more processors cause the active noise control device to perform weighted averaging of the coefficient of the secondary path filter updated according to an updating formula and the updated values in the updated value table.

6. The active noise control device according to claim 1, wherein the one or more processors cause the active noise control device to update the coefficient of the secondary path filter, by using, as the previous value, a value obtained by adding the coefficient of the secondary path filter after the previous updating of the coefficient of the secondary path filter and the read updated value at a predetermined ratio.

7. The active noise control device according to claim 1, wherein the one or more processors cause the active noise control device to:

determine whether an abnormality or divergence has occurred in the active noise control, at end of the active noise control;

store result values of the coefficient of the secondary path filter into a result value table in association with the frequency, in a table format; and

rewrite the result values in the result value table with the updated values of the updated value table when it is determined that an abnormality or divergence has occurred in the active noise control.

8. The active noise control device according to claim 1, 5
wherein the one or more processors cause the active noise control device to:

make an adjustment so as to increase magnitude of the second estimated anti-noise signal used for generation of the second virtual error signal; 10

make an adjustment so as to reduce magnitude of the estimated noise signal used for generation of the second virtual error signal;

make an adjustment so as to reduce magnitude of the first estimated anti-noise signal used for generation of the first virtual error signal; or 15

make an adjustment so as to increase the magnitude of the estimated noise signal used for generation of the first virtual error signal.
